UNITED STATES PATENT OFFICE.

SAMUEL R. PERRY, OF WILKES-BARRÉ, PENNSYLVANIA.

PIANO-ACTION.

SPECIFICATION forming part of Letters Patent No. 406,405, dated July 2, 1889.

Application filed December 8, 1888. Serial No. 293,011. (No model.)

To all whom it may concern.

Be it known that I, SAMUEL R. PERRY, a citizen of the United States of America, residing at Wilkes-Barré, in the county of Luzerne and State of Pennsylvania, have invented certain new and useful Improvements in Piano-Actions, of which the following is a specification, reference being had therein to the accompanying drawings.

This invention has relation to piano-forte actions, and may be applied to horizontal or upright pianos, with slight mechanical modifications to suit the position of each style; and it has for its object, first, to cheapen the construction thereof by dispensing with several parts usual to other forms of piano-actions; secondly, to make it more responsive to the touch, producing a better repetition of stroke in rapid execution; thirdly, to make each stroke a mechanical certainty by having each and every part directly connected one to the other; fourthly, to make a more durable and wearable action and one that will require less labor and frequency of adjustment.

To these ends the nature of the invention consists of the combinations of parts, including their construction, substantially as hereinafter fully described and claimed.

In the accompanying drawings, Figure 1 illustrates a view in side elevation of my improved piano-forte action. Fig. 2 is a modification thereof. Fig. 3 is another modification of the same.

In constructing my invention I employ, in connection with the key A, as usual, the regulating-block B, the latter being connected to the former by means of screws in the ordinary manner. This block is used to regulate the dip of the key A.

C is a pitman or rod, flexibly connected or jointed to the inner end of the key, as at a, by a leather hinge or otherwise.

In a slot in the pitman or rod C is pivoted the outer or lower end of an arm D, the inner or upper end of the arm having thereon a pin or projection b, which enters an aperture in the lower end of the damper-lever E. From this it will be seen that when the key A is pressed upon, it will cause arm D to force the damper away from the piano-string to allow free vibration of the latter, while the key is held in its depressed position.

The damper-lever E has the usual pivotal connection with the piano-forte rail F. The pitman or rod C is pivoted at its extreme upper end in a horizontal bar or lever G, intermediately of the ends of said lever or bar. The outer end of the lever or bar G is pivoted in the slotted lower end of an arm or flange d, applied to a rail H of the piano-forte. The rail H also supports a regulating check-screw I, having a cushioned block I', the function of which will appear farther on.

To the pivoted bar or lever G is connected a short link J, which in turn is connected to the lower end of a long link K, having its upper end connected or pivoted to the hammer-butt L.

The hammer-butt L may be pivoted to a flange e of the rail F, or otherwise adjusted in position.

It will thus be seen that I form a perfectly continuous connection between the key A and the hammer-butt L.

It will also be seen that the links J and K are substituted in lieu of several parts as used in the ordinary piano-forte. They combine the offices of the jack, check-damper, and tapes or bridles, and form a connection between all the parts, thus causing the action of the key to impart its force to every part simultaneously and instantly without loss of motion.

To the rail F is connected one end of a suitable spring f, the opposite end of the latter being applied to the link K. The link K carries a regulating screw and block O, which acts upon a post or arm P of the lever G, for throwing the small link J outwardly past a perpendicular line passing through the pivotal point between said link and lever, thus unlocking the stroke at a given or desired point in the movement.

The operation is as follows: When the key A is pressed by the finger, it acts upon the pitman or rod C, and the latter acts upon the arm D, removing the damper away from the string. Simultaneously the links K and J are lifted, moving the hammer away from the hammer-rail Q and throwing it against the piano-string R. As the hammer comes within a short distance of the string, the short link J is carried outward beyond the aforesaid perpendicular line, by means of the post P

coming in contact with the regulating-block O, throwing the link K against the regulating-block I', thus holding the link K firmly and the hammer in the desired position to 5 allow the free vibration of the piano-string, the key being held in its depressed position. The regulating-screws O and I are for adjusting the distance between the hammer and the piano-string, while the spring f has the effect 10 to bring the links K and J into position immediately after the removal of the finger from the key A. As the short link J is intended to unlock the hammer where desired, it is not essential that it shall be applied to the lower 15 end of the link K, as a similar result may be had by its application to the other end of said latter link and to the hammer-butt, by suitably rearranging the screws for unlocking the links. I therefore do not restrict myself to 20 the first described or preferred form of carrying out my invention as the only way of practicing it.

In the above-referred-to modification, as disclosed in Fig. 2, I have shown a cushioned 25 seat applied to the lever or bar G for the link K to rest on, and a pin passing through the lower part of the link to steady its motion, so that when the post P is pressed against the regulating-block O it will cause the link K to 30 slide off the cushioned seat of the lever G, and thus unlock the hammer at any desired point, as before mentioned in the capacity of the ordinary jack, which is a variety of Fig. 1.

In Fig. 3 I show another variety of the same

mode of disconnecting or unlocking the link 35 K by means of a small pulley x, pivoted within the regulating-block B, so as to have the link K roll over the center or pivot at the proper time, when the regulating-screw o may come in contact with a similar pulley x', secured to a rail, as shown. 40

Having thus described my invention, I claim—

1. The piano-forte action having the links J and K, connected to the hammer-butt, and 45 arm G, pivoted to the pitman of the key, substantially as and for the purpose set forth.

2. The piano-action having the arm G, pivoted upon the key-pitman, post P, applied to said arm, and the link J, connecting said arm 50 to the link K, connecting with the hammer-butt L and acting upon the cushioned regulating screw I, substantially as and for the purpose set forth.

3. The piano-forte action having the spring 55 f, connected to the link K, substantially as set forth.

4. The piano-forte action having the links J and K, combined with the arm or lever G, the pitman C, and arm D, for the purpose 60 specified.

In testimony whereof I affix my signature in presence of two witnesses.

SAMUEL R. PERRY.
